(57) **CLAIM**

I claim the ornamental design for a reservoir bladder dryer, as shown and described.

DESCRIPTION

FIG. 1 is a rear isometric view of the reservoir bladder dryer invention;

FIG. 2 is a rear isometric view of the reservoir bladder dryer invention with a reservoir bladder dryer mounted thereon;

FIG. 3 is a first side elevation view of the reservoir bladder dryer invention;

FIG. 4 is a second side elevation view of the reservoir bladder dryer invention;

FIG. 5 is a front elevation view of the reservoir bladder dryer invention;

FIG. 6 is a rear elevation view of the reservoir bladder dryer invention;

FIG. 7 is a top view of the reservoir bladder dryer invention; and,

FIG. 8 is a bottom view of the reservoir bladder dryer invention.
